UNITED STATES PATENT OFFICE.

HARRY E. RHOADS, OF TOLEDO, OHIO, ASSIGNOR TO THE WILLYS-OVERLAND COMPANY, OF TOLEDO, OHIO, A CORPORATION OF OHIO.

INTAKE NOZZLE.

Application filed September 7, 1920. Serial No. 408,696.

My invention relates to improvements in intake nozzles and particularly relates to improved means for feeding gas to an internal combustion engine.

5 One of the objects of my invention is the provision of means permitting the use of a leaner mixture.

Another object of my invention is to cause an acceleration of gases passing through 10 the intake valve chambers of the engine, one purpose being to prevent condensation of the heavier particles.

Another object of my invention is the provision of a means for retarding certain particles of the gas in order to thoroughly commingle them with the more accelerated particles of gas in the intake valve chamber.

Still another object of the invention is to provide a means located in the intake valve 20 chamber and in close proximity to the intake valve to cause a rapid flow of gases to the engine.

Further objects of the invention relate to economies of manufacture and details of 25 construction, as will hereinafter appear from the description to follow.

The objects of the invention are accomplished in one instance by the devices and means described in the following specification, 30 but it is evident that the same may be varied without departing from the scope of the invention as pointed out in the appended claims.

A structure constituting one embodiment 35 of the invention which may be the preferred is illustrated in the accompanying drawing forming a part of the specification in which:

Figure I is an elevation of an engine part 40 ly in section showing an embodiment of my intake nozzle.

Figure II is a vertical section of an intake port showing another embodiment of my invention.

45 Figure III is a vertical section of an intake port showing still another modification of the nozzle.

Like reference characters refer to similar parts throughout the several views of the 50 drawing.

In the preferred embodiment of my invention, 1 designates an L-type multi-cylinder engine having a cylinder 2, combustion space 3 and an intake port 4 with a poppet

valve 5 controlling the admission of gases 55 to the engine from the intake manifold 6. The intake manifold receives mixture thru a conduit 7 passing between the cylinders and a carburetor 8. Heated air is supplied to the carburetor thru a conduit 9. An intake nozzle 10 projecting through the intake port is held in position by means of a shoulder 11 on the nozzle placed in a groove 12 formed at the intersection of the manifold with the intake port. From the shoulder 11 the nozzle projects inwardly into a valve chamber 13 in the shape of a truncated cone 14, said cone 14 forming a venturi having a narrow inner end 15 partially closed by an annular flange or baffle 16.

The nozzle 17 in Figure II, another embodiment of my invention, is similar to the nozzle of Figure I except that no annular flange partially encloses the inner end 18 of the nozzle. This elimination of a flange or baffle requires a greater inclination in the sides 19 of the nozzle in order to reduce the opening to a size such as to insure a proper acceleration of gases passing through the nozzle.

A similar effect will result in still another modification as shown in Figure III. A ring 21 placed in the groove 12 at the intake port 4 is partially closed by a flange or baffle 22, the flange having an opening therein permitting the gases to be drawn into the intake valve chamber.

The operation of my device is as follows:

When a column of gas is drawn by suction thru the manifold and reaches one of the intake ports of the several cylinders, it must pass through the nozzle located at that port. The baffle or flange on the nozzle checks the flow of gases traveling along the periphery of the column and causes them to surge inwardly towards the center providing for a more intimate mixture. The inner and outer particles of the column of gas are differentially accelerated when they reach the nozzle due to pressure at the narrow opening in the flange, and the gases pass rapidly from the valve chamber to the engine.

The nozzle is adapted to be inserted in the intake valve chamber directly in front of the intake valve and as previously stated, 105 its function is to accelerate or speed up the flow of gas as it passes into the combustion chamber. The nozzle or baffle is adapted for

use in internal combustion engines equipped with any type of carburetor and serves to eliminate the building up of heavy particles of fuel in the intake manifold and valve chamber especially when the engine is idling or running at low speed. It is well known that when internal combustion engines are idling or are running at comparatively low speeds, that the suction or vacuum created by the piston in the combustion chamber is not sufficient to draw up and properly mix the heavy particles of fuel, and that the same will condense in the intake manifold and throat of the carburetor. Upon speeding up the engine, these heavy particles of fuel will be drawn into the engine and will result in either "killing" the engine or improper combustion. Because of the restricted opening in the nozzle, the fuel will be drawn into the combustion chamber with an increased velocity, thus relieving the building up of raw fuel in the manifold. Further, the lighter particles of gas will be readily drawn through the opening in the baffle or flange and the heavier particles will be thrown against the end wall or baffle of the nozzle, thus retarding the same and causing them to become thoroughly mixed with the lighter particles before fuel is admitted to the combustion engine.

Because the heavy particles of fuel are thoroughly mixed with the lighter fuel and because the fuel is drawn into the combustion chamber at increased velocity, it will be readily seen that a leaner mixture is required than would otherwise be the case since the crowding of gases in the nozzle provides for a more intimate mixture and the venturi effect in the nozzle causes an acceleration of the mixture to the engine. Thus a rapid discharge of an intimate mixture takes place directly in the intake valve chamber.

The forms of the device shown in Figs. I and III are preferable to that shown in Fig. II because of the flanges or shoulders 16 and 22 respectively. These shoulders which are substantially at right angles to the gas flow direct the liquid fuel deposited on the walls of the manifold, toward the center of the accelerated gas stream and the edges of the shoulders act as collectors from which the fuel is forcibly directed toward the engine. The shoulders may be formed integral with the manifold and accomplish the same result but the device herein described is adaptable to existing

engines in which condensation and distribution troubles are present.

While I have shown and described my invention in more or less detail, and as being embodied in certain precise forms, I do not desire or intend it to be limited thereto, as on the contrary, my invention contemplates broadly all proper changes as well as the omission of immaterial elements and the substitution of equivalents as circumstances may suggest or necessity render expedient.

What I claim as new and desire to secure by Letters Patent is:

1. An internal combustion engine, having an intake manifold for conducting fuel to the engine, an intake port, an intake valve chamber, a groove formed at the intersection of the manifold and the port, an intake nozzle projecting into said chamber and provided with a shoulder located in said groove, the said nozzle being shaped like a truncated cone and having an annular baffle located on the smaller end. 70

2. An internal combustion engine, having an intake manifold for conducting fuel to the engine, an intake port, an intake valve chamber, a groove formed at the intersection of the manifold and the port, an intake nozzle projecting into said chamber and provided with a shoulder located in said groove, and a flange located on said nozzle for causing a surging and an acceleration of the fuel passing from the chamber. 80

3. An internal combustion engine, having an intake manifold for conducting fuel to the engine, an intake port, an intake valve chamber, a groove formed at the intersection of the manifold and the port, an intake nozzle projecting into said chamber and provided with a shoulder located in said groove, the said nozzle being shaped like a truncated cone and having the smaller end partially closed. 90

4. In an internal combustion engine, a cylinder provided with an intake valve chamber, a valve at the discharge end of said chamber, and a cone-shaped nozzle positioned within said chamber and adapted to accelerate the flow of fuel therethrough when the valve is open, said nozzle having a portion adapted to direct the flow of the heavier particles of fuel passing along its walls into the stream flowing through the nozzle. 100

In testimony whereof, I affix my signature.
HARRY E. RHOADS.
